UNITED STATES PATENT OFFICE.

EDGAR GREENWOOD AND JOSEPH GREENWOOD, OF BRADFORD,
ENGLAND.

DABBING MECHANISM USED IN WOOL-COMBING OR THE LIKE.

No. 838,321.

Specification of Letters Patent.

Patented Dec. 11, 1906.

Application filed September 13, 1905. Serial No. 278,353.

RELIED UPON

To all whom it may concern:

Be it known that we, EDGAR GREENWOOD and JOSEPH GREENWOOD, subjects of the King of Great Britain and Ireland, whose 5 postal address is 52 Cumberland road, Lidget Green, Bradford, in the county of York, England, have invented certain new and useful Improvements in and Relating to Dabbing Mechanism Used in Wool-Combing 10 or the Like, of which the following is a specification.

This invention relates to improvements in "dabbing" mechanism used in wool-combing or the like, and has for its object the construction and arrangement of an adjustable automatic dabbing apparatus, which may be applied, by preference, to any Noble's wool-combing machine in such a manner that the use of brushes which are liable to 15 great wear and tear is obviated and that should hard or bulky substances pass to the combs either along with the wool or the like or accidentally such substances will cause the "dabber" to lift automatically and allow 20 them to pass without injury to the combs or dabber.

In describing our invention in detail reference is made to the accompanying sheet of drawings, similar letters indicating similar 25 parts, in which—

Figure 1 represents a side elevation of the mechanism employed. Fig. 2 represents a sectional plan on line *a b* of Fig. 1. Fig. 3 represents an end elevation, and Fig. 4 is a 30 section on the line *4 4* of Fig. 1. Figs. 5, 6, 7, and 8 are detail views.

In carrying out our invention the pillar A, which is that portion of the framework of a Noble's comb which projects above and 40 through the center of one of the small comb-circles, is partially surrounded by bracket B, such bracket being substantially Y-shaped, as shown in Fig. 2. The base *B'* of the said bracket is turned upward, as shown in Fig. 1. 45 Such upturned portion engages with a similar upturned portion C of bracket D, which is provided with a slot C', Fig. 8. A set-screw or the like C² passes through slot C' into portion B' for purposes of adjustment should 50 such be required. The bracket D terminates in a bearing D'.

Attached to the bracket B by means of set-screws B² or the like is another bracket E,

which abuts against the pillar A and is partly circular in shape. Guide-faces E' are formed 55 at the sides thereof. The upper portion of bracket E carries the driving mechanism of the dabber, such mechanism consisting of driving-pulley F, which actuates a shaft F' and crank F² or other eccentric movement. 60 The crank F² is surrounded by the boss G' of connecting-rod G, such connecting-rod terminating in a foot G², provided with a slot H', with which engages the adjustable rod H. The rod H is of suitable length and is formed 65 square toward its lower end, as shown at H². A conical hole J is formed in one of the squared faces of the rod H for the purpose hereinafter described.

The rod H passes through an aperture K', 70 formed in the dabber-carrier K. Such carrier is attached to or forms part of the Y-shaped lever L, the two arms of which terminate in bearings L'. A shaft M passes through these bearings into bearing D', above 75 referred to. The shaft M may be withdrawn when required.

The dabber itself consists of a suitable number of knives N and N', the knives N being for the smaller comb-circle and N' for the 80 larger one.

The knives N are mounted on small pins 0² and the distance apart of such knives regulated by sleeves 0⁵ on the said pins. Such pins may form part of the arms O or consist 85 of bolts passing through the same. The arms O pass upward into recesses or slots O² in the dabber-carrier K and are held firmly in position by means of nuts or the like O⁴, which may be loosened when required, and 90 the knives N moved toward or from the pillar A and retained in the adjusted position by means of adjusting nuts and screws, as O', or in any other convenient manner. Two knives are shown in the drawings; but it 95 must be understood that any desired number may be used.

The knives N' are arranged a suitable distance apart on rods P, and holes P' are provided in knives N' to allow the rods P to pass 100 through same. The ends of rods P are retained in sockets Q, attached to the dabber-carrier K, and set-screws Q' provided, whereby the said rods, and thereby knives N', may be adjusted and fixed.

The knives N may be arranged in such a

manner that they may be adjusted as to distance apart without removal from the carrier.

The arms of lever L are provided with adjustable screws or the like R, which act on guide-faces E' in order to prevent any longitudinal movement of the dabber.

Immediately below the surface K' in dabber-carrier K is a hollow boss S, Fig. 4, 10 screwed internally for some little distance at S', said boss S being integral with the carrier K.

A pin T, terminating in a conical end T', passes through boss S, such pin being provided with collars U' and U², U' being fixed 15 and U² being loose, and a spiral spring U surrounds the said pin between such collars. An external threaded collar V engages the thread S' at the end of boss S, such collar being provided with a cross-cut V', as shown.

20 A lock-nut V² surrounds the projecting thread of collar V. The pin T is provided with a cross-pin T² and a handle T³. The conical end T' of the pin engages with the conical aperture J in rod H and may be brought out of contact by pulling the handle T³ and turning the pin T² out of engagement 25 with the cross-cut V'.

An adjusting-screw W is provided opposite the pin T, such screw having a ball W' and ball-race W², provided, as shown in Fig. 4, in order to retain the rod H in position.

Bolts X are provided in the pillar A, and slots X' are formed in the bracket E for the reception of the same. The bracket E is provided with a foot Y and a coiled spring Z and rods Z' placed between such foot and the plate Y', attached to the dabber-carrier K, as shown in Fig. 1.

In operation the mechanism is placed in 40 position around pillar A and adjusted as to alinement by means of set-screw C². The rod H is also adjusted and the requisite number of knives N and N' placed in the required 45 position. The bases of these knives at the top of the stroke project a slight distance below the top of the comb-pins. The conical end T' of pin T engages with the conical hole J. The pulley F is then driven in any convenient manner and the connecting-rod G 50 operated, causing the rod H to move the dabber-carrier K up and down, such dabber-carrier being centered by means of the Y-

shaped lever L on shaft M. The spring Z is alternately compressed and relaxed by the action of the dabbing motion, and the relaxation of the same naturally tends to assist the movement. The rod on which the spring is mounted is to serve the purpose of a guide and support for the spring. Should any hard bulky body pass along with the combs, 55 the knives N or N' will tend to be raised. This will cause the end T' of pin T to leave the conical hole J, and the knives will be raised, thus allowing the obstruction to pass under and clear of the knives. The carrier K will then resume its original position, the pin T' returning automatically to aperture J. Should the knives require to be raised, the pin T may be drawn out, as before described, and the carrier raised. A further stop or 60 catch l may be provided in the upper portion of carrier K whereby the said carrier may be held in the raised position.

It will be understood that for a Noble's comb two of the above-described apparatus 65 will be required.

What we claim as our invention is—

1. A dabbing-machine comprising a carrier K, a reciprocating rod G, a rod H adjustably connected to the rod G, said rod H having a conical hole therein, a pin T slidably mounted in the carrier K, a spring for normally holding said pin with its point in engagement with the conical hole and antifriction means on the carrier K coacting with 80 the rod H.

2. In combination with the bracket E, a second bracket D adjustably secured thereto, a shaft M carried by the bracket D, a carrier K connected to said shaft, knives adjustably mounted on said carrier, an adjustable rod H yieldingly connected to said carrier, means carried by the bracket E for reciprocating the rod H and a spring supported on the bracket for assisting the travel of the carrier K. 90

In witness whereof we have hereunto set our hands in the presence of two witnesses.

EDGAR GREENWOOD.
JOSEPH GREENWOOD.
